UNITED STATES PATENT OFFICE

153,767

DESIGN FOR A COMBINED PERFUME
BOTTLE AND CONTAINER

René Denis, Paris, France, assignor to Societe a Responsabilite Limitee: Franco Continentale des Parfums, Paris, France, a corporation of France

Application October 6, 1947, Serial No. 141,765
In France June 27, 1947

Term of patent 3½ years

(Cl. D58—9)

To all whom it may concern:

Be it known that René Denis, a citizen of the Belgian kingdom, residing at Paris, Department of the Seine, State of France, 11 Rue du Cirque, has invented a new, original, and ornamental Design for a Combined Perfume Bottle and Container, of which the following is a specification, reference being had to the accompanying drawing, forming part thereof.

Fig. 1 is a perspective view of a combined perfume bottle and container, showing my new design;

Fig. 2 is a perspective view of a combined perfume bottle and container, the container being in open position.

I claim:

The design for a combined perfume bottle and container, as shown.

RENÉ DENIS.
